Design No. 730
by Mr. Charles - Design
for Dr. Saks and End 20th St. or Elmhurst Queen
of India Stores
Manufactured by Peter A. Schmidt, New York

Design No. 730

Des. 730

George W. Chambers of Troy N.Y.
a pignor to
Peter A. Palmer of Troy, N.Y.
Petters Patent No 730. Dated Sept 18th 1855.

The schedule referred to in these Letters Patent, and making part of the same.

To all whom it may concern:

Be it known, that I, George W. Chambers of the City of Troy
in the County of Rensselaer, and State of New York, have invented, or produced a new and original
design, for the side and end plates of an elevated Oven of a Cook Stove, which I call "The Valley Im-
proved, or Queen of Stoves"; and I do hereby declare that the following is a full, and exact de-
scription of the same; reference being had to the annexed drawings, making a part of this
specification, in which figure 1. is an elevation of a side plate; figure 2. a section through z z',
in figure 1. figure 3. a section through y y', in figure 1. - figure 4. an elevation of
an end plate; figure 5. a section through x x', in figure 4; and figure 6. a section through
w w', in figure 4.

The same letters refer to like parts in all the figures.

My ornamental design of side and end plates of an elevated oven con-
sists in the combination and arrangement of the moldings, and ornaments thereof as follows.
The ogee molding, a, along the perimeter of the outside elevated cylindrical portion A, of the side
plate, and along the outer edge of the flat stationary part B, of the end plate; the cavetto or hollow
molding b, surrounding the cylindrical surface, of the sunk panel, D. The foliage ornaments
c, at the lower corners d, d, at the top corners, e, e, at the middle of the ends, and f at the
middle of the bottom part of the side plate; the foliage ornaments g, g, g, g, at the corners, and h,
h', h', h, at the top and bottom sides of the sunk panel, D, thus bordering the central portion
thereof, wherein the name of the Stove may be set; the compound molding i, composing the
border of the oven door, l, of the end plate; and the foliage ornaments k, k', themon, disposed
so as to mostly enclose, in connection with the ornament h, a flat heart shaped tablet on
which the name of the manufacturer may be displayed.

Having thus described my design, what I claim as my invention
or production, and desire to secure by Letters Patent, is the ornamental design and
configuration of the side and end plates, of an elevated Oven of a Cook Stove, the same as here-
in described, and represented in the annexed drawings.
